TABLE LEG CLAMPING BRACKET

Denis F. White, Indianapolis, Ind.

Application May 25, 1949, Serial No. 95,317

4 Claims. (Cl. 248—221)

1

This invention relates to a clamping device which can be clamped to a post.

An important object is to provide a device for detachably clamping a horizontal shelf to a vertical post such as a table leg in the absence of screws or bolts, whereby the shelf may be adjustably positioned and secured vertically of the leg simply by pushing the shelf into its horizontally disposed position and pushing down a shelf member.

This invention has a number of possible uses, but is particularly well adapted to provide a portable shelf which can be clamped to the leg of a table such as a card table, to support an ash tray or a glass.

Further objects and advantages of the invention will become obvious to those skilled in the art from the following description of one particular form of the invention as shown in the accompanying drawings, in which

Fig. 1 is a top plan view of a device embodying the invention secured to a vertical post indicated in section;

Fig. 2 is a view in side elevation thereof;

Fig. 3 is a view in section on the line 3—3 in Fig. 1;

Fig. 4 is a view in section on the line 4—4 in Fig. 2; and

Fig. 5 is a top plan fragmentary view of the device embodying the invention, as applied to a cylindrical post.

The same numerals refer to the same parts throughout the several views.

A U-shaped body 10 formed from a suitable resilient material such as rubber is provided with laterally spaced arms 11 and 12 connected by a web 13. The free ends of the arms 11 and 12 are provided with inwardly extending projections 14 and 15 arranged substantially at right angles to said arms. The arms 11 and 12, web 13 and the projections 14 and 15 define therebetween a rectangular opening corresponding closely to the cross-sectional area of a post or leg 21, Figs. 1 and 2. The exact length of the projections 14 and 15 one toward the other may vary with the hardness and resiliency of the material used to form the body 10 and with the cross-section of the post 21. When the body is formed from rubber of 90 durometer hardness and the post has a square cross-section, the projections will have substantially the proportions as shown in Fig. 1.

It is intended that the legs 11 and 12 may be resiliently spread apart to straddle the post 21 and permit the projections 14 and 15 to pass across the sides of the post 21 and engage on the back side of that post when the web 13 is pushed against the outer or front side of the post 21, whereupon the legs 11 and 12 will spring back to come into contact with the respective sides of the post 21, as indicated in Figs. 1 and 2.

2

A pair of rods 22 and 23 formed from a suitable rigid material such as metal extend throughout the legs 11 and 12 respectively in an imbedded manner to extend through the body 10 and emerge in spaced apart relation one from the other to extend freely for a distance from the body.

A spacer bar 26 formed from any suitable substantially rigid material such as a plastic, is revolvably mounted on the rod 22 by having the rod 22 slidably pass through a bearing head 27 on one end of the bar. The bearing head 27 has washers 29 and 30 at opposite ends thereof fixed longitudinally of the rod 22 to hold the head against travel along the rod 22. These washers are held against travel away from the ends of the head 27 by staking the rod 22 outside of the washers as at 31 and 32.

The bar 26 is provided with a groove 28 across its free end, with an upwardly and outwardly sloping face 29 extending from the underside of the bar to the lower side of the groove 28. This face 29 and the groove 28 are spaced from the head 27 such that when the bar 26 is revolved about the rod 22, the lower portion of the face 29 may strike the rod 23, and, upon forcing the bar 26 further in that travel, the face 29 will relatively wedge over the rod 23 and then have the groove 28 drop around the rod 23 to hold it in that wedged over position relative to the rod 22. That is, the bar 26 spreads apart those rods 22 and 23 by their free ends, and that action rocks the imbedded portions of the rods toward each other, thereby forcing the legs 11 and 12 into a tight, compressive engagement with the post 21.

The bar 26 may carry any desired element thereon, herein shown as a shelf member 35 which is formed integrally with the bar 26 to be on the top of said bar and arranged to be in a horizontal plane when the member 35 is engaged in the slot 28, Figs. 1-4.

A horizontal disposed annular ring 36 is carried by the body 10 to be spaced above and concentrically positioned over the shelf 35 when the rod 23 is engaged in the slot 28. The ring 36 acts as a guard for articles (not shown) placed on the shelf 35.

To clamp the device to the vertical post 21 the rod 23 is relatively removed from the slot 28 and the free ends of the rods 22 and 23 are compressed inwardly toward each other. The projections 14 and 15 on the arms 11 and 12 are thereby spread apart a sufficient distance to permit the projections and arms to be fitted around the post 21 by lever action of the shafts 22 and 23 acting through the body 10. After the body 10 has been fitted around the post 21 the compression on the outer free ends of the rods is released and the rod 23 is relatively replaced in the slot 28.

Upon application of a load (not shown) to the shelf 35, the exposed portions of the rods 22 and 23 are tended to be depressed slightly downward. Cocking action through the body 10 compresses the web 13 and the projections 14 and 15 against the post 21 and tends to resist in itself downward travel of the device along the post 21. Therefore with each increase in load on the shelf the gripping action of the body 10 on the post 21 is increased and the body is secured in its original position on the post.

A U-shaped adaptor 38 formed from any suitable material such as rubber is used to convert the body 10 for use with a cylindrical post 39. The adaptor is provided with opposed legs 46 and 41 joined by a web 42, and the legs are provided with inwardly extending projections 43 and 44 on their free ends. The adaptor is formed to fit tightly within the legs 11 and 12, projections 14 and 15, and web 13 of the body 10. The adaptor is centered between the arms 11 and 12 and formed to fit tightly around the post 39 to circumscribe approximately 75 per cent of the horizontal perimeter of said post.

After the adaptor is installed in the body 10 the device is applied to the post 39 in the same manner as the unconverted body 10 is applied to the post 21.

While I have herein shown and described my invention in one particular form it is obvious that structural changes may be employed without departing from the spirit of the invention, and I therefore do not desire to be limited to that precise form beyond the limitations which may be imposed by the following claims.

I claim:

1. A clamping device for securing a horizontal shelf to a vertical post comprising a U-shaped body provided with opposed arms and a web connecting the arms, each of said arms being provided with inwardly extending projections on its free ends, said arms, web, and end projections being made of elastic rubber formed to fit tightly around the major portion of the horizontal perimeter of a post; a rigid rod having a portion imbedded centrally in one of said arms to continue on through the body by an exposed portion extending from the web end of the body; a second rigid rod having a portion imbedded centrally in the other of said arms to continue on through the body by an exposed portion extending from the web end of the body; a rubber spacer bar pivotally mounted on the exposed portion of one of said rods and having a slot in a free end to engage the other member, said bar having a length between said rods to require forcing of the bar between the rods to effect said engagement; and a shelf mounted on the top side of said bar.

2. A clamping device for securing a horizontal shelf to a vertical post comprising a U-shaped body provided with opposed arms and a web connecting the arms, each of said arms being provided with inwardly extending projections on its free ends, said arms, web, and end projections being formed to fit tightly around the major portion of the horizontal perimeter of a post; an elongated member having a portion imbedded centrally in one of said arms and having an exposed portion extending from the web end of the body; a second elongated member having a portion imbedded centrally in the other of said arms and having an exposed portion extending from the web end of the body; a spacer bar pivotally mounted on the exposed portion of one of said members and having a slot in a free end to en-

gage the other member, said bar being arranged to prevent relative movement of the members toward each other when the other member is engaged in the slot; said shelf being secured to the top of the spacer bar in such a manner as to be held in a horizontal position when the spacer bar is engaged with the other elongated member.

3. A clamping device for securing a horizontal shelf to a vertical post comprising a U-shaped body provided with opposed arms and a web connecting the arms, each of said arms being provided with inwardly extending projections on its free end, said arms, web and end projections being formed to fit tightly around the major portion of the horizontal perimeter of the vertical post; a first rigid rod having a portion imbedded centrally in one of said arms and having an exposed portion extending from the web end of the body; a second rigid rod having a portion imbedded centrally in the other of said arms and having an exposed portion extending from the web end of the body, each of said rigid rods being normally held in substantially parallel relation by the body; a spacer bar rotatably mounted on said first rod in a position spaced from the body and having a slot in a free end formed to receive the second rod and so arranged that when the second is engaged in the slot relative movement of the rods toward each other is prevented; said shelf being secured to the top of the spacer bar in such a position as to have its top surface in a horizontal plane when the second rod is engaged in the slot.

4. A clamping device for securing a horizontal shelf to a vertical post comprising a U-shaped body provided with opposed arms and a web connecting the arms, each of said arms being provided with inwardly extending projections on its free ends, said arms, web, and end projections being formed to fit tightly around the major portion of the horizontal perimeter of a post; an elongated member having a portion imbedded centrally in one of said arms and having an exposed portion extending from the web end of the body; a second elongated member having a portion imbedded centrally in the other of said arms and having an exposed portion extending from the web end of the body; a spacer bar pivotally mounted on the exposed portion of one of said members and having a slot in a free end to engage the other member, said bar being arranged to prevent relative movement of the members toward each other when the other member is engaged in the slot; said shelf being secured to the top of the spacer bar in such a manner as to be held in a horizontal position when the spacer bar is engaged with the other elongated members; an annular ring carried by the body in a position over the shelf.
